UNITED STATES PATENT OFFICE.

HERMANN BIENERT, OF BEUTHEN, GERMANY.

ELECTRIC SAFETY LOCK.

Application filed February 6, 1926. Serial No. 86,674.

This invention relates to a lock comprising a locking of the locking hook adapted to be electrically released, in which the alternating current circuit for exciting the 5 electro-magnet may be switched in from outside or inside the house or flat, from the inside by a press-button (or switch) from the outside by means of a contact known only to the initiated and to be adjusted by 10 a threaded key.

The electric safety lock is independent of any ordinary lock and can be mounted on any kind of door provided an electric light plant exists.

15 In the accompanying drawings—

Fig. 1 shows the electric safety lock partly in front elevation and partly in section on line 1—1 of Fig. 2.

Fig. 2 is a section on line 2—2 of Fig. 1.

20 Fig. 3 is a section on line 3—3 of Fig. 1.

Fig. 4 is a section on line 4—4 of Fig. 1.

The leading in wires 1 and 1' from the 25 electric lighting plant which enter into the upper part of the safety lock terminate at the contact springs *a* *b* of a push button *c* said contact springs being each connected with one pole of the electro-magnet *k*. Under the electro-magnet *k* an armature lever *d* is pivotally mounted which co-operates with a locking hook *e* fixed on the 30 door post.

If from inside the door the button *c* is pushed the circuit of the electro-magnet *k* is closed and the lever *d* is attracted by the 35 electro-magnet whereby the lock is unlocked so that by means of the latch key or the door handle the door can be opened.

To open the safety lock from the outer 40 side of the door a key has to be inserted into a hole bored through the door at the height of the push button *c* said hole having an inner diameter of about 4 mm. corresponding to the outer diameter of the key *i*. In the key a nut is fixed which is to be screwed 45 upon a threaded stud fixed on the contact spring *a* so that this contact spring is pulled against the contact spring *b* closing the circuit through the electromagnet *k* so that the lever *d* is attracted and the locking hook 50 *e* released.

It is difficult to imitate the key as in an impression of wax the threads will be destroyed when the wax impression is taken

out. The lock issues when opened a rather loud buzzing noise which frightens the 55 house breaker, and the lock may further be connected with an alarm signal.

In case of short-circuit or failing of current it would not be possible to open the lock from the outer side of the door. For 60 this reason a spring device *f* is arranged. The spring *f* is compressed by a safety pin *g*. This pin *g* has a diameter of 1 to 2 mm. and is located in a narrow hole bored 65 through the door. If a pin is inserted into the narrow hole *p* covered at the outer end by wax of the same colour as the door is painted (Fig. 4) the pin *g* is pushed out so that the spring *f* is no longer retained and pushes the lever *d* up so that the locking 70 hook *e* is released. If the electric line is in order again the safety pin *g* is reinserted into the hole *g*.

To render the safety lock inoperative a 75 short arm *h* is pivotally mounted underneath the lever *d*, said arm being normally in the position shown in Fig. 1 in full lines. If this arm is rotated 90° into the position shown in dotted lines in Fig. 1, the arm *h* lifts the lever *d* and maintains it in this 80 lifted position. To render the safety lock operative the arm *h* is returned into the initial position.

I claim:—

An electric safety lock comprising in combination a locking hook fixed on the door post, a lock plate fixed on the door, an electromagnet on said door plate, a lever pivotally mounted under said electromagnet so that it is normally in locking engagement 85 with said locking hook, two contact springs on said plate above said electromagnet said contact springs being inserted in an electric circuit fed from the electric light plant, a push button on the inner one of said contact springs, and a threaded pin on the other side of said inner contact spring, said pin projecting into a hole bored into the door so that a key with a nut fitting on said threaded pin can be inserted through said 90 hole for pulling the said contact spring against the other contact spring to close the circuit so that the safety lock can be 95 opened from the outer side of the door.

In testimony whereof I affix my signature.

HERMANN BIENERT.
